UNITED STATES PATENT OFFICE.

SAMUEL OLSON, OF CHICAGO, ILLINOIS, ASSIGNOR TO SAMUEL OLSON & COMPANY, OF CHICAGO, ILLINOIS, A CORPORATION OF ILLINOIS.

SELECTIVE-SWITCH SYSTEM FOR CONVEYERS.

Application filed May 29, 1922. Serial No. 564,348.

To all whom it may concern:

Be it known that I, SAMUEL OLSON, a citizen of the United States, and having residence at Chicago, in the county of Cook and the State of Illinois, have invented certain new and useful Improvements in Selective-Switch Systems for Conveyers, of which the following is a specification, reference being had to the accompanying drawings, forming 10 a part thereof.

This invention relates to automatic switching devices for conveyer systems and its object is to provide means associated with each load carrier or car of the system for causing it to be automatically diverted from the conveyer at a selected station thereof. It 15 consists of the features and elements of construction and their combination hereinafter described and shown in the drawings, as indicated by the claims.

In the drawings:—

Figure 1 is a top plan view of a conveyer with a portion between stations broken out to condense the figure and showing switching devices embodying this invention applied thereto.

Figure 2 is a side elevation of a portion of the structure shown in Figure 1, viewed from the plane indicated at line 2—2, 30 thereon.

Figure 3 is a transverse section taken as indicated at line, 3—3, on Figure 2.

Figure 4 is a side elevation similar to Figure 2, showing a modified construction.

Figure 5 is a transverse section taken as indicated at line, 5—5, on Figure 4.

Figure 6 is a plan view of another modification of the invention showing it applied to a conveyer at two stations.

Figure 7 is a side elevation of a part of the structure shown in Figure 6, as viewed from the plane indicated at line, 7—7, thereon.

Figure 8 is a detail section taken as indicated at line, 8—8, on Figure 6.

It may be understood that the loads to be carried by the horizontal conveyer belt, 1, are disposed in load carriers or boxes, 2, of uniform dimensions and construction, and that laterally associated with the conveyer belt, 1, there will be a plurality of stations such as those indicated by the platforms, 3 and 4, each extending laterally from the path of the belt, 1, preferably provided with a roller, 5, interposed to fa-

cilitate movement of the load-carrying boxes from the belt onto the station platform. In diverting any box, 2, from the normal direction of travel in which the belt, 1, moves, the frictional driving force of the conveyer belt is employed in conjunction with the guiding effect of an obliquely disposed switch bar, 6, which is temporarily moved to extend across the belt, 1, in the path of an approaching carrier box, 2.

In the form of the invention shown in Figures 1, 2 and 3, each carrier box, 2, is provided with a plurality of trip dogs, 7, pivotally carried upon a rod or bar, 8, which extends across the front end of the box, 2, so that the several trips, 7, are spaced laterally across the box, each occupying a definite position at a certain distance from the sides of the box. At each station a rock shaft, 9, is journaled to extend over the belt, 1, above the path of the boxes carried thereby, and such rock shaft has a rigidly depending trip arm, 10, extending low enough to encounter a certain one of the dogs, 7, on any of the carrier boxes, 2, if the dog be adjusted 70 to its upper position projecting above the top of the box. Thus, as the box, 2, travels under the rock shaft, 9, the upwardly projecting dog, 7, by encounter with the trip arm, 10, rocks the shaft and swings its rocker arm, 11, to move the link, 12, and crank arm, 13, by which the switch bar, 6, is suddenly thrown across the belt, 1, in the path of the box, 2, for diverting the box laterally over the roller, 5, and onto the station platform.

Preferably each of the dogs, 7, is formed with a bent tail piece, 7a, providing a delay surface which holds the switch bar, 6, in its operative position against the pull of the retracting spring, 14, until the box or carrier, 2, actually encounters the bar in the relation illustrated in Figure 1 opposite the station, 3. It should be understood that at each station the depending trip arm, 10, is disposed in a different position transversely of the belt, 1, and that only one of the trips, 7, will be swung to its upward position at any time on any one load carrier box, 2. Therefore, the remaining trips, 7, of the box are inoperative for the time being, and the station trip arms, 10, which do not register with the single elevated trip, 7, will be inoperative as to that particular load carrier, and will permit it to pass the station with- 110

out interference. Obviously, individual load carriers, 2, could be provided each with a single trip device, 7, adapted for switching purposes at one station only, but 5 it is preferable to fit each load carrier, 2, with a complete set of trips, so that it may be routed to any station of the series as desired by simply elevating the proper trip, 7.

Figures 4 and 5 illustrate a modification 10 in which the station trip arm is a lever, 15, fulcrumed on a horizontal pivot, 16, but depending below the top level of the load carrier, 20, and at one side of it for encounter with a laterally projecting button 15 or roller, 21, on the carrier, 20. The switch bar, 6^a, is operated substantially as in the first described form of the invention through a connecting link, 22, the pivotal mounting of the bar not being shown in the drawing. 20 At the station platform, 3^a, a roller, 5^a, is provided and the belt construction of the conveyer is exactly the same as in Figure 1. Instead of providing a plurality of trip members, 21, the load carrier, 20, is fitted 25 with a plate, 23, having a plurality of holes, 24, at respectively different heights, so that the trip member, 21, may be shifted into any of these holes to register with the trip lever, 15, at any particular station, these 30 trip levers being either fulcrumed at different heights, or being made of different lengths, so as to extend within different distances of the plane of the conveyer belt. This arrangement thus provides for routing 35 a carrier box, 20, to any particular station simply by shifting its trip button, 21, into the proper hole, 24.

Figures 6, 7 and 8 illustrate a third form 40 of the invention, in which the trip lever, 25, swings about the vertical axis of a rock shaft or pivot, 26, instead of upon a horizontal axis, and extends over the box or load carrier, 30. A switch bar, 6, is mounted to swing upon a vertical axis 45 exactly as in Figure 1, and its movement is controlled by a link, 27, connecting with the trip lever, 25. The carrier, 30, actuates the trip arm, 25, by means of an upstanding trip or post, 31, preferably mounted in a 50 socket fitting, 32, secured to a side wall of the box, and to avoid lateral displacement of the carrier, 30, during this action, as well as undue friction upon the lateral 55 guide wall, 33, an antifriction roller, 34, may be mounted opposite the trip lever, 25, to engage the opposite side wall of the box as it passes this point. The bent end, 25^a, of the lever, 25, serves as a delay surface to hold the switch bar, 6, at its obliquely 60 extending position across the belt, 1, until the further corner of the box has encountered it. Thereafter, of course, the pressure of the box against the switch bar, 6, will hold it in position until the box has 65 passed over the roller, 5, and on to the sta-

tion platform; then a retracting spring, 14, will return the bar to a position alongside the path of the belt, as shown in the right-hand portion of Figure 6.

The trip levers, 25, at different stations 70 of the system illustrated in Figure 6, will be disposed at different levels or distances above the plane of the belt, 1, so that unless the post, 31, of a particular load carrier, 75 30, is high enough to reach the level, 25, at a given station, the box, 30, will pass on without being deflected from the belt. By arranging the station levels, 25, in a graduated series, with the highest one 80 nearest the starting end of the belt run, and with the lowest one farthest removed from this point, the carrier boxes, 30, may be routed to any desired station by adjusting their trip posts, 31, to different heights. For this purpose, the post is made with a plurality of spaced apertures, 35, so that a cross pin may be slipped through any one of these 85 apertures, just above the top of the socket, 32, to hold the post more or less elevated to register with the proper trip arm, 25. 90

I claim:

1. In a belt conveyer, a load carrier to travel on the belt, a station laterally adjacent the path of belt travel, a switch bar movably mounted to permit of adjustment 95 obliquely across the belt opposite said station for shunting a load carrier off the belt toward said station, and means on the load carrier for so adjusting the switch bar.

2. In the combination defined in claim 1, the adjusting means being arranged to automatically move the switch bar into oblique position as the load carrier approaches it.

3. In a belt conveyer, a load carrier to travel on the belt; a plurality of stations laterally adjacent the path of belt travel with a switch bar at each of said stations movably mounted to permit of adjustment obliquely across the belt for shunting a load carrier off the belt toward the station; an actuating member for each switch bar extending adjacent the path of travel of the load carrier on the belt, and means projecting from the load carrier adapted to engage such actuating member of one of the switch bars, whereby the carrier will be selectively shunted off to the station at that switch. 110

4. In the combination defined in claim 3, the different actuators being differently located in relation to the path of the load carrier, said carrier having fixed means projecting for encounter with one selected actuator, but dimensioned to avoid contact with the other actuators which it passes in traveling toward said selected actuator on the belt. 120

5. In the combination defined in claim 3, additional load carriers adapted for travel on the belt, and each provided with projecting means adapted to engage an actuating 125 130

- member of one of the switch bars, said actuators being differently located in relation to the path of the load carriers, and the projections of the different load carriers extending different distances for encounter with the actuators selectively. 5 pending therefrom, together with an up-standing projection on the carrier to encounter such actuator for rendering the switch device operative with respect to said carrier. 40
6. In a belt conveyer, a load carrier to travel on the belt, a station laterally adjacent the path of belt travel, a switch member associated with the station in normally inoperative position, and means on the carrier for adjusting said switch member into operative position as the carrier approaches it for causing the switch member to shunt the carrier off the belt toward the station. 10
7. In a belt conveyer, a plurality of load carriers to travel on the belt, a plurality of stations laterally adjacent the path of belt travel, a switch device associated with each station and normally inoperative; actuating means for each switch device extending adjacent the path of travel of the load carriers on the belt, the different actuators being differently located in relation to said path 20 of the carriers, and co-operating means on the carriers located at different positions respectively for selective encounter with the actuators at the various stations. 25
8. In the combination defined in claim 7, the co-operating means on each carrier being adjustable for registration with any selected actuator. 30
9. In a belt conveyer, a load carrier to travel on the belt; a station laterally adjacent the path of belt travel, a switch device associated with said station and normally inoperative, an actuator for the switch device mounted to swing about a horizontal axis above the path of the carrier and de- 35
10. In the combination defined in claim 9, additional load carriers and additional stations with a switch device for each station, the actuators of the switch devices being disposed at different positions transversely of the belt, and the projecting means of the respective carriers being adapted to be presented at different transverse positions respectively, for selective registration with the said actuators. 45
11. In the combination defined in claim 9, additional load carriers and additional stations with a switch device for each station, the actuators of the switch devices being disposed at different positions transversely of the belt and the projecting means of each carrier, comprising a plurality of laterally spaced members adapted for individual adjustment into projecting position to adapt the carrier to actuate any selected switch. 50
12. In a belt conveyer, a load carrier to travel on the belt, and means for diverting the load carrier from the belt comprising a switch bar movably mounted to permit of adjustment obliquely across the belt for encounter with the carrier, and means on said load carrier for adjusting the switch bar to such encountering position as the carrier approaches it. 55

In testimony whereof, I have hereunto set my hand at Chicago, Illinois, this 22d day of May, 1922. 70

SAMUEL OLSON.
